UNITED STATES PATENT OFFICE

JAMES H. SKITT, OF PHILADELPHIA, PENNSYLVANIA, ASSIGNOR TO SMITH, DRUM & COMPANY, OF PHILADELPHIA, PENNSYLVANIA, A CORPORATION OF PENNSYLVANIA

FLATWORK IRONER

Application filed May 1, 1929. Serial No. 359,454.

My invention relates to flat work ironers and has for its object to provide improved means for adjusting the pressure roller frame and the apron tightening frame in such manner that the mechanisms for acting on both frames are interconnected so that the lowering of the pressure roller frame into operative position will occur simultaneously with the raising of the apron tightening frame into its operative position. Means are provided for a certain freedom of movement to allow for further adjustment of the pressure roller frame without materially disturbing the operating position of the apron tightening frame. This method of acting upon the two frames is, broadly speaking, not new with me. My invention consists in improved mechanism for effecting the results indicated, the leading feature of which is the employment of means for supporting and adjusting the pressure roll frame, and a pair of toggle links adapted when in approximately parallel positions to support the apron frame in operative position, these toggle links being actuated through means which actuate the roll frame and preferably by a rotary device in the nature of a crank or eccentric moving synchronously with the means for adjusting the roll frame and connected to the toggles through a connecting rod, the device in the nature of a crank and the connecting rod, being so adjusted as to be approximately on dead center when the links and the toggle are straightened out. Another feature of my invention consists in the use in connection with the toggle, of means for connecting the toggle with the apron frame, including a spring which is placed under increased tension as the toggles are straightened out and which tends, as the toggle links are moved away from parallel positions, to hold the apron frame in fixed position during the early part of such movement of the toggle links.

The nature of my improvements will be best understood as described in connection with the drawings which illustrate a machine provided with my improvements and in which

Figure 1 is a side elevation of the end of a

flat ironer to which the apron supporting frame is attached, the parts being shown in operative position.

Figure 2 is a similar elevation showing the parts in the position they occupy where the roll frame and apron frame are moved to nonoperative positions.

Figure 3 is a sectional view on the line 3—3 of Figure 1, showing the construction of the roll frame and the device immediately operating upon it, the steam box being omitted.

Figure 4 is a detail of features of construction of the upper toggle link and the means by which it is connected to the apron frame, the parts being shown in the position they occupy when the toggle links are in the position shown in Figure 1, and

Figure 5 is a similar view showing the parts in the position they occupy when the apron is lowered, as shown in Figure 2.

A indicates the frame-work of the machine. B is the steam box of usual construction. C is the frame which supports the ironing rolls, indicated at C¹. C², C³, indicate pins on the roller frame with which are connected connecting rods C³, on the lower ends of which are eccentric straps C⁴ connected with eccentrics D², D², secured on the shafts indicated at D and D¹. D³, D³, are crank arms secured on the shaft D¹ and D⁴ is a worm wheel, one such wheel being secured to each shaft D and D¹, through which the shafts are connected by worms E¹, E¹, on the shaft E, which shaft is at will rotated in either direction by any convenient means, that indicated in the drawings being by means of bevel wheel E² and E³, running loosely on the shaft and actuated in different directions by a gear wheel E⁴, the clutch F keyed to the shaft being at will moved to couple either of the bevel wheels to the shaft. F¹ indicates the mechanism for shifting the clutch.

G is the apron supporting frame which is pivoted to the machine frame, as indicated at G¹, and to which are connected pins indicated at G², through which the frame is supported and adjusted. The apron frame as shown is provided with slots, indicated at H and H¹, in which are adjustably supported the journal bearings H² and H³ of apron supporting

frames, these bearings being adjusted by screws indicated at H^4 , H^5 indicating guide rods on which the journal bearings run. I and I^1 indicate the apron drums supported on the adjustable bearing blocks. J is the apron supported on the frame I, the upper portion of which passes, when the machine is operated, in contact with the lower part of the steam box, to which it is directed by roller K; the lower ply of the apron passes, as shown, over the guide drums or rolls indicated at K^1 , K^2 . L indicates the lower apron supported on the drum I^1 , the upper ply passing over the guide roll K^3 and under the guide roll K^2 and the lower ply under the guide roll K^3 .

Referring next to the mechanism for actuating the apron frame, this consists of toggle links M^1 and M^2 , the lower one supported on a fixed pivot, indicated at M, and the links being coupled together by a pin indicated at M^3 . The upper link M^2 is chambered out and provided with guideways, as indicated at M^4 , the chamber enclosing a spring indicated at O^4 . At the base of the chamber in the toggle link a cross bar M^6 is formed in which is provided a seat M^7 for a nut indicated at O. Through this nut passes a screw O^1 having a squared end O^2 which screw supports a plate O^3 which in turn supports a spring O^4 . The upper end of this spring bears against a plate O^6 which moves in a guideway indicated at M^8 and in its uppermost position bears against a stop ledge indicated at M^5 and upon this plate O^6 is supported a box O^5 through which extends the pin G^2 secured to the apron frame. It will be observed that the box O^5 is free to move upward from contact with the plate M^8 through an extension of the slot formed in the upper end of the toggle link.

N is a coupling rod coupled at one end to the crank pin at the end of the crank arm D^3 and at the other end coupled, as shown, to the pin M^8 by which the toggle links are coupled together. The toggle links are so disposed that when straightened out so that they will lie approximately parallel to each other, they will hold the apron frame in operative position, as shown in Figure 1, preferably holding it in contact with a stop P. In this position the spring O^4 will be somewhat compressed and the plate O^6 moved somewhat away from the stop M^5 , as shown in Figure 4. When the toggle links are moved to the position shown in Figure 2, the spring is fully expanded and the plate O^6 in contact with the stop M^5 , as shown in Figure 5. This coupling of the toggle to the apron frame through a spring, the tension of which is increased as the apron frame is brought to operative position, enables the frame to remain in operative position for a short time after the toggle links commence their movement away from parallelism.

The toggles are actuated through the crank

arms D^2 and the links or connecting rods N and the crank D^3 are so disposed that the cranks and connecting rods are approximately on dead center when the toggle links are parallel to each other. As shown in Figure 1, the toggle links are approaching a parallel position and the cranks and connecting links are naturally approaching dead center. It will be obvious, however, that as the cranks rotate toward the right they will gradually straighten out the links and then, after passing dead center with increasing speed, shift the toggle links to the position shown in Figure 2.

It will of course be obvious that the mechanism for actuating the toggles and the described mechanism for adjusting the roll frames are interconnected, and interconnected in such a way that as the pressure roll frame is moved downward into operative position near the steam chest by the eccentrics to which it is connected, the apron roll frame is simultaneously moved upward into its operative position. This movement takes place when the crank which operates the toggle links is moving toward the upper dead center. Due to the connecting link being very short in proportion to the throw of the crank, also on account of the toggle links being approximately parallel at this point, a considerable movement of the crank operating mechanism can be made on either side of the dead center without causing any appreciable movement of the apron roll frame. This feature will enable the operator of the machine to adjust the working pressure of the rolls on the steam chest without materially disturbing the tension on the aprons.

It will be understood that the box O^5 normally remains in contact with the plate O^6 . The reason for making the box separable from the plate and giving it freedom to move upward in the slot at the end of the toggle link is to provide for a possible contingency in which some obstacle prevents the lowering of the apron frame to the full extent of its contemplated movement; in such a case, the arrested movement of the apron frame which of course arrests the downward movement of the box O^5 does not prevent the toggle link continuing its downward movement.

Having now described my invention, what I claim as new and desire to secure by Letters Patent, is:

1. In a flat work ironing machine having an adjustable frame for carrying the ironing rolls an adjustable frame for tightening and relaxing the apron, toggle links adapted to actuate the apron frame and arrange to hold the apron frame in apron tightening position while the toggle links are in substantially parallel positions and a spring located between the link connected with the apron frame and said apron frame in such manner as to be put under compression as the toggle

raises the frame to apron tightening position, in combination with means for adjusting the roll frame and means interconnecting the mechanism for adjusting the roll frame
5 with the toggle links for actuating the apron frame acting to flex the toggle as the roll frame is elevated.
2. In a flat work ironing machine having an adjustable frame for carrying the ironing 10 rolls and an adjustable frame for tightening and relaxing the apron, toggle links adapted to actuate the apron frame and arranged to hold the apron frame in apron tightening position while the toggle links are in substantially parallel positions and means for adjusting the roll frame and means interconnecting the mechanism for adjusting the roll frame with the toggle links for actuating the apron frame acting to flex the toggle as the 15 roll frame is elevated, the specific means for actuating the bell tightening frame comprising the means for directly acting on the toggle links consisting of a crank moving in unison with the means for adjusting the roll frame and a connecting rod coupling said crank to the toggle, said crank and connecting rod being so disposed as to be approximately on dead center when the toggle links are parallel, and means for connecting the 20 toggle links to the apron frame including a spring which is put under increased tension as the toggle links straighten out.

JAMES H. SKITT.
